UNITED STATES PATENT OFFICE.

ORTON G. RUST, OF SPRINGFIELD, OHIO.

SUSPENDER-END.

1,076,154.

Specification of Letters Patent. Patented Oct. 21, 1913.

Application filed January 7, 1909. Serial No. 471,071.

To all whom it may concern:

Be it known that I, ORTON G. RUST, a citizen of the United States, residing at Springfield, in the county of Clark and State of Ohio, have invented certain new and useful Improvements in Suspender-Ends, of which the following is a specification, reference being had therein to the accompanying drawings.

10 This invention relates to suspender-ends. The object of the invention is to provide a suspender-end with a cast-off which will comprise a minimum number of pieces, and, when assembled, will form a strong, durable 15 cast-off and will present a slightly appearance.

To this end a further object of the invention is to provide a cast-off comprising a body portion, a reinforcing strip and an auxiliary strap, these three members comprising but two pieces of material and being secured together by two fastening devices, thus reducing the number of pieces to be handled in assembling the device and reducing to a minimum the work of assembling the cast-off.

With these objects in view my invention consists in certain novel features and in certain combinations and arrangements of 30 parts hereinafter to be described, and then more particularly pointed out in the claims.

In the accompanying drawings, Figure 1 is a front elevation of a suspender-end embodying my invention; Fig. 2 is a detail 35 view of the combined body portion and reinforcing strip; Fig. 3 is a vertical sectional view of an assembled cast-off in which the body portion and reinforcing strip are formed integral; Fig. 4 is a sectional view 40 of a similar cast-off provided with an auxiliary supporting-strap; and Fig. 5 is a sectional view of a cast-off in which the reinforcing strip is formed integral with the supporting-strap.

45 In these drawings I have illustrated three forms of cast-off, each embodying my invention.

In Figs. 2 and 3 I have shown the cast-off as comprising a body portion 1 having 50 one of its end portions adapted to be folded upon itself, as shown at 2, and to form a loop to receive and support button straps 3, the two button straps being, in the present 55 instance, shown as formed integral. The folded over portion of the cast-off is secured to the body portion thereof by means of a

suitable fastening device, which, in the present instance, comprises one member, 4, of a head and socket fastener. A reinforcing strip 5 is secured to the folded-over end portion of the cast-off and is preferably formed integral therewith. This reinforcing strip has its other end connected to the body portion 1 of the cast-off at a point some distance removed from the folded-over end portion thereof, and, in the present instance, this end of the reinforcing strip is fastened to the body portion of the cast-off by means of the other member, 6, of the above-mentioned head and socket fastener. This fastener is preferably located some distance from the adjacent end of the body portion of the cast-off, thus causing that portion of the cast-off lying beyond the fastening device to extend beyond the folded over portion thereof and form a loop 7 which gives a finished appearance to the cast-off and conceals from view the rough or unfinished portions thereof.

In Fig. 4 I have shown a cast-off similar in construction to that shown in Figs. 2 and 3 and have shown the same as provided with an auxiliary supporting strap 8, which is secured to the cast-off at its upper end and is provided at its lower end with a suitable 80 clasp 9. The upper end of the supporting strap 8 is preferably arranged between the folded-over portion of the cast-off and the body portion thereof and is secured to the cast-off by the fastening device 4, by means 85 of which the folded-over portion thereof is secured to the body portion thereof. The strap 8 extends downwardly from its point of connection to the cast-off, about the button strap 3, which is contained within the 90 folded-over portion 2 of the cast-off, and through an aperture 10 formed in said folded-over portion. Thus, it will be apparent 95 that the completed cast-off comprises but two pieces of material, one forming the cast-off proper and its reinforcing strip and the other forming the auxiliary supporting strap. A single fastening device serves to connect one end of the reinforcing device, 100 folded-over portion of the cast-off and the auxiliary supporting strap to the body portion of the cast-off. Further, this fastening device co-operates with the other portion 6, which serves to secure the other end of the reinforcing strip to the body portion of the 105 cast-off, to form a fastener by means of which the two end portions of the cast-off 110

are connected one to the other and the cast-off secured to the end of the suspender-strap.

In Fig. 5 I have shown a slightly modified 5 form of the cast-off shown in Fig. 4, and, as there shown, instead of forming the reinforcing strip 5 integral with the folded-over end of the body portion of the cast-off I have formed this reinforcing strip 10 integral with the auxiliary supporting strap 8 and have arranged the same between the folded-over portion of the cast-off and the body portion thereof and secured the three parts together by the fastening device 4, as 15 was described in connection with Fig. 4. The strap 8 extends downwardly, about the button strap 3 and through the aperture 10, as was also described above.

From the foregoing description it will be 20 apparent that I have provided a cast-off composed of a minimum number of parts and adapted to connect the button straps and the auxiliary supporting strap to the suspender-end in a strong and durable manner and of such a construction that, when in 25 its finished condition, it will present a slightly appearance; and that I have provided a cast-off comprising a body portion, a folded-over portion, a reinforcing strip 30 and an auxiliary supporting strap, all of which are connected by means of a single fastening device, thus greatly reducing the number of pieces to be handled and the labor necessary in assembling the cast-off.

I wish it to be understood that I do not 35 desire to be limited to the details of construction shown and described, for obvious modifications will occur to a person skilled in the art.

Having thus fully described my invention, what I claim as new and desire to secure by Letters Patent, is:—

1. A one piece cast-off having a central

or body portion and upper and lower end portions, the upper end portion being turned 45 downward in front of said body portion and adapted to connect the cast-off to a suspender, the lower end portion being turned upward between said body portion and said downturned upper end portion to form a 50 loop, said lower end portion having an aperture therein near the bottom of said loop, means for securing said upturned lower end portion to said body portion, and a supporting strap secured to said body portion between the same and said upturned lower end portion and extending downward through the aperture in said loop.

2. A one piece cast-off having a central or body portion and upper and lower end 60 portions, the upper end portion being turned downward in front of said body portion and adapted to connect the cast-off to a suspender, the lower end portion being turned upward between said body portion and said 65 downturned end portion to form a loop, said lower end portion having an aperture therein near the bottom of said loop, a reinforcing strip secured to said downturned end portion near the free end thereof, extending 70 along the inner surface of said end portion and said body portion, between said upturned end portion and said body portion and having an integral extension passing through the aperture in said upturned end 75 portion and constituting a supporting strap, and a single device for securing said upturned end portion and said combined reinforcing strip and supporting strap to said body portion.

In testimony whereof, I affix my signature in presence of two witnesses.

ORTON G. RUST.
